UNITED STATES PATENT OFFICE.

GEORGE A. CARLSON, OF MOSCOW, IDAHO.

CORNER-FASTENING FOR BEDSTEADS.

No. 904,681.

Specification of Letters Patent.

Patented Nov. 24, 1908.

Application filed July 2, 1908. Serial No. 441,523.

To all whom it may concern:

Be it known that I, GEORGE A. CARLSON, a citizen of the United States, residing at Moscow, in the county of Latah and State of Idaho, have invented a new and useful Corner-Fastening for Bedsteads, of which the following is a specification.

This invention relates to corner fastenings for metal bedsteads; and has for its object to provide a simple and secure means for attaching the side rails of bedsteads to the corner posts of the head and foot sections, the construction being such that it is immaterial how the rails are presented to the posts, the fastenings thereon are certain to engage with one another and make a strong and rigid connection.

With this as the main object in view the invention consists of the novel construction and combination of parts hereinafter described and claimed, and illustrated in the accompanying drawing, in which:—

Figure 1 is a side elevation of a corner post and a part of the side rail of a bedstead illustrating the invention, a portion of the fastening being broken away; Fig. 2 a detail view in elevation of the bed post; Fig. 3 a cross sectional view of the same on the line 3—3 of Fig. 2; Fig. 4 a plan view of one end of the side rail; and Fig. 5 a perspective view enlarged of that part of the fastening device carried by the end of the side rail.

Like reference characters are used for the same parts in all the figures.

In the drawing, 1 indicates a metal bed post and 2 one of the side rails fastened thereto. The posts and rails are of well known type and need no further description.

At a proper height from the floor, that is to say the height of the side rails, the posts are each provided with three lugs 3, 4, and 5. The central lug 3 projects outwardly from the post 1, as shown in Fig. 2, while the lugs 4 and 5 extend inwardly in a direction opposite that of lug 3. See Fig. 3. Each lug is as wide as the bed post, curved on its projecting end and beveled towards the post from below upwardly.

Cast or otherwise secured on each end of the bedstead rails 2, are fastening members 6 adapted to coöperate with the lugs 3, 4, and 5 on the bed posts 1. Each member 6 comprises a head 7 provided with an extension 8 inclosing the rail end, from which extends the top and bottom sides of the

head diverge at equal angles and for a suitable distance to an integral vertically placed semi-circular casing 9 equally disposed above and below a horizontal line extending 60 through the rail 2. The top and bottom edges of the casing 9 are, when the bed is set up, in substantially the same planes as the top and bottom sides of the lugs 4 and 5 respectively.

Within the semi-circular casing 9 are two ribs, one 10 near the top of the casing and the other 11 near the bottom thereof. These ribs 10 and 11 are each beveled in opposite directions from a horizontal concave edge 70 12, see Fig. 5, and having a radius equal to that of the lugs 4 and 5. Referring to Fig. 1, it will be noted that the inner beveled side of the rib 10 and the outer beveled side of the rib 11 have the same angle as the 75 beveled ends of the lugs 4 and 5, and that the edges 12 are midway between the tops and bottoms of said lugs. Now, as the outer beveled side of the rib 10 and the inner beveled side of the rib 11 form similar but 80 opposite angles to the previously noted beveled sides, the side rail 2 will engage with and fit the lugs 4 and 5 on the bed post readily and securely whichever side of said rail is uppermost.

Projecting from the middle of one upright edge of the semi-circular casing in a plane parallel to the side rail 2 is a thin and somewhat broad arm 13 terminating in a semi-circular, or hook shaped end 14 the inner 90 radius of which is substantially the same as the radius of the lug 3 on the bed post. A rib 15 similar to the ribs 10 and 11, is formed within the curved end 14 and bears the same relation to the lug 3 that the ribs 10 and 11 95 bear to the lugs 4 and 5. The vertical edge of the semi-circular casing 9 opposite the arm 13, is cut away between the ribs 10 and 11, forming an open space 16 to enable the 100 assemblage of the post 1 and rail 2 in the following manner.

The bed post 1 is preferably raised to a vertical position and the side rail 2, supported horizontally, is moved to bring the fastening member 6 against the bed post 105 with the rib 14 above the lug 3, the space 16 opposite the lug 4 and the bottom of the casing above the lowest lug 5. The rail is then moved, towards the post which enters the space 17 between the arm 13 at one side, the 110 casing at one end and the hook shaped end 14 of the arm at the other end. As soon as

the bed post 1 and the side of the arm 13 come in contact, the side rail is dropped into place, bringing the lower beveled faces of the ribs 15, 10 and 11 in contact with and supported by the beveled ends of the respective lugs 3, 4, and 5.

A bedstead fastener constructed as above described is strong, light and serves to brace the head and foot sections against tilting lengthwise of the bed owing to the length of the bearing, and the support given on the inner and outer sides of the post by the coacting ribs and lugs. A bed can be set up and taken down very quickly when provided with the hereinabove described fastening, and will be thoroughly rigid and strong.

What is claimed is:—

1. In a corner fastening for bedsteads, a bed post provided with oppositely projecting lugs, combined with a rail having a head on each end adapted to connect with said post, said head having an arm adapted to extend around said bed post and ribs on said head and arm arranged to rest on said lugs and be supported by them.

2. In a corner fastening for bedsteads, a bed post provided with oppositely projecting lugs having their ends inclined upwardly in the direction of the post, combined with a rail having a head on each end adapted to connect with said bed post, said head having an arm on one side arranged to extend partly around the bed post and ribs on said head and arm having beveled faces to rest on the beveled ends of said lugs and be supported by them.

3. In a corner fastening for bedsteads, a

bed post provided with oppositely projecting lugs having curved ends inclined upwardly toward the post, combined with a co-operating member on the end of the side rail, said member comprising a head having a vertical semi-circular casing containing a double inclined curved rib near each end, an arm projecting from one side of said casing with a semi-circular hook on its end and a curved double inclined rib in said hook, said ribs adapted to rest on the beveled ends of said lugs when the head is in either of two positions.

4. In a corner fastening for bedsteads, a bed-post provided with oppositely projecting lugs having curved ends inclined upwardly toward the post, combined with a co-operating member on the end of a bed rail, said member comprising a head having a vertical semi-circular casing from one side of which an arm projects having a semi-circular or curved end, said curved end and casing facing each other, a double inclined rib within the casing near each end and a like rib within the curved end of said arm, their disposition being such that the co-operating member will be supported on the bed-post and locked thereto by the wedge-like surfaces of the ribs and lugs.

In testimony that I claim the foregoing as my own, I have hereto affixed my signature in the presence of two witnesses.

GEORGE A. CARLSON.
